United States Patent Office

Des. 187,380
Patented Mar. 8, 1960

187,380

PLAYGROUND DEVICE

Edgar R. Overton, Oakland, Calif.

Application September 10, 1959, Serial No. 57,503

Term of patent 14 years

(Cl. D34—5)

FIG. 2

I claim:

An ornamental design for a playground device, as shown.
